CLAIM

The ornamental design for a dispenser for tissues and hand-pulled paper products, as shown and described.

DESCRIPTION

FIG. 1 is a front perspective view of a dispenser for tissues and hand-pulled paper products showing my design; FIG. 2 is front elevational view thereof; FIG. 3 is a rear elevational view thereof; FIG. 4 is a left-side elevational view thereof; the right-side view is a mirror image of the left-side view; FIG. 5 is a top plan view thereof; FIG. 6 is a bottom plan view thereof; and, FIG. 7 is an exploded, front perspective view thereof shown in environmental use.

The dash-dot-dot lines that abut a claimed surface represent an unclaimed boundary between claimed and unclaimed surfaces. None of the broken lines form any part of the claimed design.
